(57) **CLAIM**

The ornamental design for a fishnet frame, as shown and described.

DESCRIPTION

FIG. 1 is a side perspective view of a fishnet frame, showing our new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof; and,

FIG. 7 is a bottom plan view thereof.

The dashed broken lines in the drawing depict environmental subject matter only and form no part of the claimed design.

1 Claim, 4 Drawing Sheets
